(57) **CLAIM**

The ornamental design for a rear combination lamp of car, as shown and described.

DESCRIPTION

FIG. 1 is a perspective view of new design for a rear combination lamp of car as shown in the drawings;

FIG. 2 is a front elevation view of the rear combination lamp of car;

FIG. 3 is a rear elevation view of the rear combination lamp of car;

FIG. 4 is a left side view of the rear combination lamp of car;

FIG. 5 is a right side view of the rear combination lamp of car;

FIG. 6 is a top plan view of the rear combination lamp of car;

and,

FIG. 7 is a bottom plan view of the rear combination lamp of car.
